RACQUET FOR A TETHER BALL GAME

Joseph M. Ziabicki, 2307 Mohr Ave., Racine, Wis.

Filed July 24, 1961, Ser. No. 66,031

Term of patent 14 years

(Cl. D34—5)

FIGURE 1 is a perspective view of racquet for a tether ball game embodying my new design the balance of the holes being omitted for convenience of illustration;

FIGURE 2 is a top plan view thereof, but on an enlarged scale;

FIGURE 3 is a sectional view, taken along line 3—3 in FIGURE 2, but on an enlarged scale, and

FIGURE 4 is a sectional view thereof, taken along line 5—5 in FIGURE 2, but on an enlarged scale.

I claim:

The ornamental design for a racquet for a tether ball game, substantially as shown and described.
